I claim the ornamental design for a chew toy, as shown and described.

(57) **CLAIM****DESCRIPTION**

FIG. 1 is an isometric rear view of a chew toy showing my new design.

FIG. 2 is a top plan view thereof.

FIG. 3 is a bottom plan view thereof.

FIG. 4 is a left elevational view thereof.

FIG. 5 is a right elevational view thereof.

FIG. 6 is a front elevational view thereof; and,
FIG. 7 is a rear elevational view thereof.**1 Claim, 4 Drawing Sheets****US D848,083 S**
